UNITED STATES PATENT OFFICE.

SAMUEL W. BUTLER AND ELLIOTT WASSON, OF LOCK HAVEN, PENNSYLVANIA.

DOOR-LATCH.

1,174,385.

Specification of Letters Patent. Patented Mar. 7, 1916.

Application filed March 17, 1915. Serial No. 15,026.

To all whom it may concern:

Be it known that we, SAMUEL W. BUTLER and ELLIOTT WASSON, citizens of the United States, residing at Lock Haven, in 5 the county of Clinton, State of Pennsylvania, have invented certain new and useful Improvements in Door-Latches; and we do hereby declare the following to be a full, clear, and exact description of the invention, such as will enable others skilled in the art to which it appertains to make and use the same.

This invention relates to a door latch.

An object of the invention resides in the 15 provision of a latch which will automatically lock when door is closed.

A further object of the invention resides in so constructing the latch that it will be operated as the door is opened from either 20 the inside or outside by simply pushing upon the knobs.

With these and other objects in view, such as will appear as the description progresses, our invention comprises the combination and arrangement of parts as set forth 25 in and falling within the scope of the appended claim.

Referring to the drawing: Figure 1 is an 30 elevational view of our device with one of the cover plates removed, looking from the side of the device which is to be secured to the door. Fig. 2 is a sectional view looking at the other side of the device. Fig. 3 is a sectional view taken in a plane at 35 right angles to the plane of Fig. 2 and showing the position of the operating rod and slide when the latch bolt is in its locking position. Fig. 4 is a similar view showing the latch bolt drawn into the casing.

40 Referring to the drawing like parts are indicated by like characters throughout the several views.

In the embodiment of our invention shown in the drawing, we have provided a 45 casing 1 which is of rectangular formation and has one side 2 removable. Mounted in this casing 1 is a slide 3 which operates between pins 4 at one end thereof, which pins are formed on the casing 1. A slot 5 is located in the other end of the slide 3 and a 50 stud 6, formed integrally with the casing 1, extends upwardly through the slot. The slide is thus guided in its longitudinal movement in the casing. At one end of this slide 55 a pair of upwardly extending guides 7 are provided, which are in spaced relation for

a purpose which will later appear. An elongated opening 8 is formed in the slide 3 adjacent the guides 7 and in alinement with the space between the same. A latch bolt 9 which has the usual beveled end is mounted on the slide 3 and has a reduced neck 10 which is slidable between the guides 7. On the end of this neck is a cross head 11 from which a projection 12 extends into the opening 8. The contacting of the head 11 with the inner edges of the guides 7 limits the outward movement of the latch bolt and the projection 12 guides the latch bolt 9 together with the guides 7 in its movement relative 70 to the slide 3.

In order that the slide 3 and the latch bolt 9 may be normally pressed outwardly so that the beveled end of the latch bolt will extend through the edge of the casing, we 75 have pivoted a pawl 13 to the casing 1, which pawl projects into a recess 14 in the slide 3 and the free end of which bears against the projection 12 on the latch bolt 9. This pawl is actuated by a spring 15, which bears 80 against it and against one edge of the casing 1. The movement of this pawl is limited by a stop 16 formed on the casing 1. The movement of the slide 3 is limited in one direction by the contacting of the inner end of the 85 slide with the casing and in the other direction by the contacting of a pin 17 with one of the pins 4.

In order that the latch bolt 9 may be drawn inwardly against the tension of the 90 spring 15, we have provided a cam 18 formed in a recess 19 in the slide 3, which cam extends into a cam groove 20 in an operating rod 21, which rod extends through the casing and is slidably transversely thereof. This rod is adapted to be extended 95 through the door and have the usual knobs secured to the ends thereof. The rod 21 is rectangular in cross section so that it will not be allowed to have rotative movement, 100 but its only movement will be a sliding movement through the casing. Now as the knob on the inside of the door is pulled the latch bolt will be drawn inwardly because of the fact that the slide 3 will be forced inwardly by the riding of the cam 18 in the groove 20. The operation of the rod 21 from the opposite side of the door will of course be reversed, inasmuch as it will be necessary to push the rod inwardly to cause 110 the cam 18 to ride in the groove. The door may then be opened by a continued push

or pull upon the handles and when the rod 21 is released the spring 15 will return the latch bolt 9 and the slide 3 to their initial positions. As the door closes the latch bolt 9 will be pushed inwardly against the tension of the spring 15 without causing the movement of the slide 3. This is allowed because of the fact that the latch bolt may have relative movement, as respects the slide. This movement of the latch bolt 10 allows the door to close easily since it is not necessary for the latch bolt to move the cam 18 in the groove 20, which would require considerable force and tend to prevent the latching of the door.

In order that the closing of the door may be facilitated, we have provided the keeper 23 with a roller 24 on which the beveled end of the latch bolt 9 rides.

20 It will be seen that we have provided a latch by means of which a door will be secured in its closed position, but which may be operated to allow the door to open by merely pushing or pulling upon the knobs.

25 While we have illustrated and described a particular embodiment of our invention, we have merely done so for the sake of convenience and we do not wish to be limited

to that particular embodiment as it is obvious that numerous changes may be made within the details of construction thereof without in any way departing from the spirit of the invention or exceeding the scope of the appended claim.

35

What we claim is:—

In a door latch, the combination with a casing, of a slide operable therein, said slide having a pair of spaced guides on one end thereof and an opening therein in alinement with the space between the guides, a latch bolt having an elongated neck slidably mounted between the said guides and a cross head arranged to engage the inner faces of the said guides, a projection extending from the cross head and into the said opening in the slide, and resilient means for maintaining the latch bolt and slide in such position that the cross head will engage the guides.

40 In testimony whereof, we affix our signatures, in the presence of two witnesses.

SAMUEL W. BUTLER.
ELLIOTT WASSON.
